US0D1085888S

(12) United States Design Patent (10) Patent No.: US D1,085,888 S
(45) Date of Patent:  *Jul. 29, 2025

(54) PACKAGING BAG

(71) Applicant: TIMAC AGRO INTERNATIONAL,
Saint-Malo (FR)

(72) Inventor: Anne Monnerie, Saint-Malo (FR)

(*) Notice: This patent is subject to a terminal disclaimer.

() Term: 15 Years

(21) Appl. No.: 35/520,984

(22) Filed: Mar. 22, 2024

(80) Hague Agreement Data

Int. Filing Date: Mar. 22, 2024

Int. Reg. No.: DM/236959

Int. Reg. Date: Mar. 22, 2024

Int. Reg. Pub. Date: May 24, 2024
